UNITED STATES PATENT OFFICE

135,700

DESIGN FOR A CIGARETTE HOLDER RING

Jacob M. Bock, New York, N. Y.

Application August 11, 1942, Serial No. 107,880

Term of patent 7 years

To all whom it may concern:

Be it known that I, Jacob M. Bock, a citizen of the United States, residing at 124 Cannon Street, New York, county and State of New York, have invented a new, original, and ornamental Design for a Cigarette Holder Ring, of which the following is a specification, reference being had to the accompanying drawing, forming a part thereof.

In the drawing:

Fig. 1 is a side elevational view of a cigarette holder ring showing my new design;

Fig. 2 is an end elevational view thereof, as indicated by arrow 2 in Fig. 1;

Fig. 2a is a elevational view of the end opposite that shown in Fig. 2, and indicated by arrow 2a in Fig. 1;

Fig. 3 is a top plan view;

Fig. 3a is a bottom plan view; and

Fig. 4 is a fragmentary sectional view on an enlarged scale taken transversely through the cigarette holding portion of the device.

I claim:

The ornamental design for a cigarette holder ring, as shown.

JACOB M. BOCK.
